Primary Examiner — Sheryl Lane(74) Attorney, Agent, or Firm — Daniel L. Fitch, Esq.(57) CLAIM

We claim the ornamental design for an eleven bulb pin tray, as shown and described.

DESCRIPTION

FIG. 1 is a front perspective view showing the new design;
 FIG. 2 is a front view thereof;
 FIG. 3 is a rear view thereof;
 FIG. 4 is a left side view thereof;
 FIG. 5 is a right side view thereof;
 FIG. 6 is a top view thereof; and,
 FIG. 7 is a bottom view thereof.

The broken lines in the figures depict portions of the eleven bulb pin tray that form no part of the claimed design.
